UNITED STATES PATENT OFFICE.

DANIEL W. BARTON, OF OSHKOSH, WISCONSIN.

ELECTRICALLY-OPERATED MUSICAL INSTRUMENT.

1,298,864.

Specification of Letters Patent.

Patented Apr. 1, 1919.

Application filed September 16, 1916. Serial No. 120,455.

To all whom it may concern:

Be it known that I, DANIEL W. BARTON, a citizen of the United States, and resident of Oshkosh, in the county of Winnebago and 5 State of Wisconsin, have invented new and useful Improvements in Electrically-Operated Musical Instruments, of which the following is a description, reference being had to the accompanying drawings, which are a 10 part of this specification.

This invention relates to improvements in electrically operated musical instruments.

It is one of the objects of the present invention to provide an electrically operated 15 musical instrument which may be played by a person not a musician without producing discordant sounds.

A further object of the invention is to provide an electrically operated musical instrument in which a person unskilled in music 20 may produce a great variety of different musical sounds and harmonious tones.

A further object of the invention is to provide an electrically operated musical instrument having a keyboard portion spaced 25 from the instrument proper and connected thereto by a flexible connector to permit the keyboard to be placed where desired.

A further object of the invention is to provide 30 an electrically operated musical instrument in which the units of the tone producing portion or instrument proper, are tuned with relation to each other in thirds, fifths and octaves so that the actuation of 35 any combination of units will produce harmonious chords and thus prevent discords.

A further object of the invention is to provide 40 an electrically operated musical instrument which is more particularly although not solely, adapted for automobile use; and is provided with means for easy and convenient attachment thereto.

A further object of the invention is to provide 45 an electrically actuated and manually controlled musical instrument of the xylophone type which is of simple construction, is strong and durable and is well adapted for the purpose described.

With the above and other objects in view 50 the invention consists of the improved elec-

trically operated musical instrument and its parts and combinations as set forth in the claims and all equivalents thereof.

In the accompanying drawings in which the same reference characters indicate the same parts in all of the views:

Figure 1 is a side view of the improved electrically operated musical instrument, the casing being shown in section and the electrical connections being shown partly in diagrammatic form;

Fig. 2 is a similar view of the opposite side of the instrument disconnected from the key board;

Fig. 3 is a transverse sectional view of the instrument taken on line 3—3 of Fig. 1;

Fig. 4 is a transverse sectional view of the keyboard; and

Fig. 5 is a diagrammatic view of the electrical connections.

Referring to the drawings the numeral 8 indicates the musical instrument proper, 9 the casing thereof, 10 the cover and 11 the keyboard for controlling the playing of the instrument. The musical instrument preferably comprises a plurality of sound-producing units 12 of the xylophone type but may be formed of any other sound-producing devices desired. The units 12 consist of vertically extending steel xylophone bars 13 mounted in front of resonators 13' which in turn are mounted upon a transverse supporting bar 14. Cushioning means or pads 15 are interposed between the resonators and the cross bar and the casing in order to prevent discordant tones from the units. Tubes 16 forming part of the resonators are closed at their outer ends and some of said tubes are provided with extension tubes 17 to give the desired tone.

The steel bars 13 are loosely mounted on the resonators by cushioned screws 18 which extend through openings 19 adjacent the upper ends of the bars. The lower ends of the bars are loosely engaged by angular rubber covered pins 20 which maintain the bars in operative position.

Cushions 21 space the steel bars 13 from the board 13'.

Each resonator 13' is provided with an

upwardly extending arm 22 on which is mounted an electromagnet 23 having a vibrating armature 24 provided with a hammer 25. The hammer extends to a position 5 to engage its respective xylophone bar 13 so that when the hammer is vibrated by the armature the bar will be struck and a musical sound produced.

The casing 9 is provided with a plurality 10 of apertures 9' to permit the free passage of sound from the casing.

The electromagnets may be of any form desired but are preferably of the double coil type as shown and are controlled by the key-board 11.

The keyboard 11 comprises a base board 26 having upstanding eyed members 27 through which extends a rod 28. Keys 29 pivotally mounted at their rear ends on the rod 28 are provided at their front end portions with downwardly projecting screws 30 which extend through elongated openings 31' of a perforated plate 31 mounted on the base board and also through small washers 32 resting on the plate. The heads 30' of the screws are of larger diameter than the openings through which the screws extend and serve as stops to limit the upward swing of the keys. Coiled springs 33 surrounding 30 the screws 30 and interposed between the keys 29 and the washers 32 and the plate 31 maintain the keys yieldingly in their uppermost position. Washers 34 surrounding the coiled springs 33 and interposed between the 35 keys and the plate limit the downward swing of the keys.

While any number of keys may be used, seven keys are preferably used for controlling the five musical units C, E, G, octave 40 C, and octave E, 12 shown. Contact buttons 35 mounted on the base board, one beneath each of the first five keys, starting at the left, are connected by circuit wires 36 with the respective electromagnets 23 they are 45 adapted to control. The electromagnets are also connected to the common return wire 37 which leads to and is connected to the battery or other source of electrical current 38. A wire 39 connected to the opposite side of 50 the battery is grounded on the eyed bolts 27 and the rod 28 to which the keys 29 are connected. The keys 29 are connected to the rod 28 by eyed metal strips 40 which extend to positions beneath the keys to electrically 55 engage the contact buttons 35 when the keys are depressed and thus form electrical connections with their respective electromagnets.

Beneath each of the last two keys 29' and 60 30' are positioned four contact buttons 41 and 42 which are connected to the electromagnets preferably in the combinations shown although other combinations may be

used. In the present structure the tones C, E, G, octave C, and octave E are employed. 65 The tones are all in proper musical relation with each other in all combinations in which they may be played. As shown the seventh or last key 29' is connected to four of the tones C, E, G, C, which when pressed gives 70 the C chord; the second last key 29' is connected to four tones E, G, C and E to give the C chord and its inversions. When these two keys are pressed at the same time, the result is two C's in octaves, two E's in octaves and G, giving an entirely different musical result. One of the keys is connected to C, one to E, one to G, one to octave C, and one to octave E. 75

The keyboard 11 is preferably provided with a clamping means 43 for attaching the board to an automobile part, for instance the steering column to permit convenient playing thereof.

It will thus be seen that a person with no knowledge whatsoever of music, may at will play a great number of musical tones, chords and bugle calls, and that it will be impossible to make a discord. In the present structure the tones used are the same as 85 used in all regulation bugle calls so that the instrument is adapted to be used by a person with musical talent if desired. 90

It is to be understood that the tones need not be tuned in relation to each other as in the present structure but may be tuned in any manner to be always in harmony with 95 each other in all combinations in which they may be played.

From the foregoing description it will be 100 seen that the musical instrument is of very simple construction and is well adapted for the purpose described.

What I claim as my invention is:

1. A musical instrument, comprising a 105 plurality of sound producing units arranged in proper musical relation with each other in all combinations in which they may be played to produce only harmonious sounds when a plurality of the units are electrically 110 vibrated, and means distant from the units for controlling the actuation of the units.

2. A musical instrument, comprising a 115 plurality of electrically actuated sound producing units arranged in proper musical relation with each other in all combinations in which they may be played to produce only harmonious sounds when a plurality of the units are actuated, a keyboard distant from the units for controlling the continuous vibration of said units, and an electric circuit including a source of electrical current in which the keyboard and the sound producing units are included.

3. A musical instrument, comprising a 125 plurality of electrically actuated sound pro-

ducing units arranged in proper musical relation with each other in all combinations in which they may be played to produce only harmonious sounds when a plurality of the 5 units are actuated; electromagnetic means for vibrating the units, a keyboard for controlling the actuation of said units, said keyboard having a plurality of keys some of which control individual units and others of

which control a plurality of units, said units 10 when actuated causing a continuous harmonious sound, and an electric circuit including a source of electrical current in which the keyboard and the electromagnetic means are included. 15

In testimony whereof, I affix my signature.

DANIEL W. BARTON.
